DESIGN FOR A PROJECTILE-DROPPING BOMB-SIGHT TOY

Glenn W. Isgrig, Cincinnati, Ohio

Application November 8, 1944, Serial No. 116,212

Term of patent 14 years

(Cl. D34—15)

To all whom it may concern:

Be it known that I, Glenn W. Isgrig, a citizen of the United States, residing at Cincinnati, in the county of Hamilton and State of Ohio, have invented a new, original, and ornamental Design for Projectile-Dropping Bomb-Sight Toys, of which the following is a specification, reference being had to the accompanying drawings, forming part thereof.

Fig. 1 is a side perspective view of a projectile-dropping bomb-sight toy showing my new design. Fig. 2 is an opposite side perspective view thereof.

I claim:

The ornamental design for a projectile-dropping bomb-sight toy, as shown.

GLENN W. ISGRIG.
